UNITED STATES PATENT OFFICE.

FRED H. ALLEN, OF AUBURN, MAINE.

PLATE-PRINTING PRESS.

SPECIFICATION forming part of Letters Patent No. 445,150, dated January 27, 1891.

Application filed March 8, 1889. Serial No. 302,496. (No model.)

To all whom it may concern:

Be it known that I, FRED H. ALLEN, a citizen of the United States, residing at Auburn, in the county of Androscoggin and State of Maine, have invented certain new and useful Improvements in Plate-Printing Presses; and I do hereby declare the following to be a full, clear, and exact description of the invention, such as will enable others skilled in the art to which it appertains to make and use the same.

My invention relates to plate-printing presses such as are used for printing copper and steel plates.

15 The object of my invention is to construct a plate-printing press which shall have the feeding mechanism outside the standards, thereby giving more room for the plate between the standards and thus increasing the 20 capacity of the press and avoiding use of oil near the plates.

25 My invention consists in the combination of an outrigger attached to the side of the bed, a stud or roll secured to said outrigger, an arm secured to the impression-roll journal, and a cam adjustably secured to said arm and adapted to impinge on said stud and to release it at any desired point.

30 My invention consists of the combinations of devices set forth in the claim.

I illustrate my invention by means of the accompanying drawings, although I do not wish to be confined to the exact structure here shown.

35 In the drawings, Figure 1 is a plan view of a press embodying my invention. Fig. 2 is a section on line xx of Fig. 1. Fig. 3 is a side elevation, and Fig. 4 is a detail, of the arm and stud at the point when the latter is let off.

40 A is the frame-work of the machine.
B is the movable bed.

A' A' are the standards, to which are journaled the shaft or journal g of the impression-roll G.

45 D is the hand-wheel for rotating the impression-roll.

The above-named parts are all of ordinary and well-known construction and do not require more particular description.

50 To the side of the bed B, I attach an outrigger C, which extends outside of the stand-

ard A'. I prefer to drop this outrigger somewhat below the level of the bed, for the reason hereinafter mentioned.

To the outrigger C, I attach a stud or roll 55 f , and this I prefer to make adjustable lengthwise of the outrigger by means of a slot e , through which the bolt f^2 extends, and which is secured by a nut f^2 on the inside.

An arm E is adjustably secured to the journal g . This I accomplish, as herein shown, by forming the arm with a disk E', which fits around the shaft and within a recess formed on the inside of the hub of the hand-wheel D. This disk is free to turn on the journal and 65 is clamped in any desired position by means of a set-screw d , passing through the hub of the wheel D and impinging on the disk E'.

To the end of the arm E, I secure a cam e , formed to strike the stud f in a direction as 70 nearly in line of motion of the bed as may be. The cam is placed on the inside of the arm, so that as it drops on being rotated it passes completely under the stud f , letting it off or releasing it from contact with the cam e . The 75 arm E is placed far enough away so that it clears the stud. As here shown, I secure the cam e to the arm E by means of a bolt e^2 , passing through a slot e^2 , so that it may be adjustable to any desired position. It is obvious that I can use an outer friction-roll or a rigid stud for the cam e to operate upon.

The operation of my device is evident from its structure, as explained. As the wheel D is rotated the cam e impinges on the stud or 85 roll f , forcing the bed forward until the impression-roll is in position to take the paper, when the cam drops below the stud and thus releases it and allows the impression-roll to continue the movement of the bed. As will be 90 seen, the length of the arm E, which is occasioned by the dropping of the outrigger below the bed, gives to the latter a rapid motion from the start to the point of contact with the impression-roll, thereby saving much time 95 and adding to the capacity of the press. It is obvious that the arm E must be adjusted circumferentially on the journal g , the cam adjusted on the arm E, and the stud on the outrigger, in order to cause the cam to let off 100 at just the right point, which, as before pointed out, must be at the moment of contact of

the roll and the plate. Since the cam strikes the stud in the line of motion of the bed, or nearly so, as pointed out, there is no tendency to tilt or otherwise disturb the bed, and as a result my press works much more smoothly than those hitherto in use.

Another advantage of my press is that the space between the standards is left free from obstruction, so that the paper may fill the whole space. A press embodying my invention is thus able to do larger work than an old press of the same size, and the danger of spoiling the prints by oil and grease is also obviated, since the space occupied by the paper is now entirely free from lubricants.

I claim—

In a plate-printing press, the combination of a movable bed, an outrigger attached to the side thereof, a stud or roll secured to said outrigger, an arm secured to the impression-roll journal, and a cam adjustably secured to said arm and adapted to impinge on said stud and to release it at any desired point, substantially as shown.

In testimony whereof I affix my signature in presence of two witnesses.

FRED H. ALLEN.
